ABSTRACT: The invention is a press utilizing transfer dies for rapidly assembling badges or similar items made from laminar material. The transfer dies are hollow and shaped to register with each other. A first die having a sharpened wedge-shaped edge performs the functions of cutting badge material to size and then holding the badge material in its hollow interior. Second and third dies, arranged to successively register with the first die, each include a piston which pushes cut badge material into the first die where the material is accumulated until a complete badge is formed.

FIG-2FIG-3FIG-4

BADGE PRESS

BACKGROUND OF THE INVENTION

The invention relates to the field of transfer dies and more particularly to the field of transfer dies used in a press for rapidly forming laminated objects such as identification badges and the like.

Although presses for forming identification badges have been known for a long time, the presses of the prior art usually require the insertion and reinsertion of various portions of an identification badge in several separate steps. Typically a badge is formed using prior art methods by first preparing a face plate then subsequently preparing identification indicia and lastly preparing a backing plate. These steps usually require several manual operations including the operations of cutting and then pressing or crimping the badge together. If this operation is performed in a press a first set of dies is usually used for the cutting function and a second set of dies is usually used for the badge assembly function. Apart from the delay involved in changing dies or alternatively, in using different presses, there is and has been a greater likelihood of error in badge making due to the large number of manual steps which have heretofore been necessary.

An object of the present invention has been to device a badge press which performs the functions of both cutting and assembling identification badges in a single relatively low cost apparatus.

SUMMARY OF THE INVENTION

The above object is achieved with a set of dies mounted in a press or frame so that a first die can come into registry with the remaining dies, one at a time. Each of the remaining dies is mounted on the frame or press for motion in a path transverse to the motion of the first die whereby each of the remaining dies can achieve registry with the first. The first die has an internal structure such as a wedge shaped cylindrical edge suitable for both cutting badge material and holding badge material transferred to the interior of the aforesaid first die. The remaining dies, equipped to support material to be transferred, include a material transfer means, such as a piston, for urging material into the internal structure of the first die when one of the remaining dies is in registry with the first die.

Finally, a press means, such as a lever, is mounted on the frame for applying force to the first die to achieve registry between dies and then activate the piston means. Accordingly, material held in the first die after successive registry with the remaining dies will be pressed together forming a completed badge. The apparatus will be more clearly understood with reference to the FIGS.

BRIEF DESCRIPTION OF THE DRAWINGS

FIG. 1 is a perspective view of the apparatus of the invention.

FIG. 2 is a side cutaway view of the apparatus illustrated in FIG. 1.

FIG. 3 is a view of a portion of the base of the apparatus as seen looking in the direction of the arrows 3-3 in FIG. 2.

FIG. 4 is a badge of the type assembled in the apparatus shown in FIG. 1.

FIG. 5a is a side cutaway view of the first and second spaced dies with laminar badge material placed between the dies.

FIG. 5b is a side cutaway view of the first and second dies cutting material therebetween to a size approximately equal to the inner circumference of the second die.

FIG. 5c is a side cutaway view of the first and second spaced dies with the piston pin shown in FIG. 5a and a badge face placed on the material previously cut.

FIG. 5d is a side cutaway view of first and second dies in registry.

FIG. 5e is a side cutaway view of first and third spaced dies with a badge back placed in the third die.

FIG. 5f is a side cutaway view of first and third dies in registry thereby completing the badge assembly.

DESCRIPTION OF THE PREFERRED EMBODIMENT

With reference to FIG. 1 the badge press 11 of the present invention is seen to comprise a set of dies 12, 13, 14 mounted on a frame 16. A force means, such as the lever 17 is arranged to transmit force to the first die 12 through the shaft 18. The first die 12 is mounted for motion from the upper portion 19 of the frame toward the lower portion 21. The second and third dies 13, 14 are mounted on the lower portion 21 of the frame in a manner so that each die can come into registry with the first die 12. The motion of the dies 13, 14 is arranged to be reciprocatively rotary on a swing arm 25 pivoting about the pivot point 22 on a curve which is transverse to the motion of the first die 12, although any motion which will rapidly align the first die 12 with each of the remaining dies is acceptable.

The theory of operation of the press 11 calls for laminar badge materials to be placed in the second and third dies 13, 14 and to be transferred successively to the first die 12 wherein a complete badge is formed. Since badge materials must first be cut to size the apparatus includes a cutting means which will be understood with reference to FIG. 2.

In FIG. 2 the profile of the dies 12, 13, 14 is apparent. The first die 12 is seen to be mounted to the shaft 18 just below the fixed collar 23. Apertures 24, 26 in the collar 23 provide sights for visually aligning the first die 12 which may be turned on the threads 27 of shaft 18. The lugs 28, 29 provide references on the first die 12 for optically referencing the angular position of that die with respect to the fixed collar 23.

The first die 12 defines a hollow central portion 31 and a downwardly projecting cylindrical edge 32 having a pointed wedge-shaped cross section with the wedge point facing a registering die. This structure enables the first die 12 to cut materials of a diameter greater than the cylindrical edge 32 which are placed in the press between the first die 12 and the die positioned beneath it, in this case the second die 13.

The dies 13, 14 mounted on the lower portion 21 of the frame each comprise a hollow cylinder surrounding a piston 33, 34 respectively. Each of the dies 13, 14 is telescopically mounted relative to the piston 33, 34 which it surrounds. Each of the pistons 33, 34 is fixed relative to the swing arm 25. Each of the springs 36, 37 resting against an annular projection on each of pistons 33, 34 supports a protrusion on a respective die 13, 14 causing the dies 13, 14 to be suspended and free to move downwardly, coaxially over a respective piston, when force is applied from above, e.g. from the first die 12.

The second die 13 and the associated piston 33 define a common hole through both members for accommodating a removable pin 38 forming a locking means. When the pin 38 is in place the second die 13 is immovable relative to the piston 33. This locking feature available in the second die 13 enables the downwardly projecting edge of the first die 12 to move against and through laminar badge materials to be cut without movement of the badge materials during cutting. When the pin 38 is removed, the second die 13 can move downwardly as mentioned above.

Each piston 33, 34 defines an elongated axial slot 39, 40 through which a pin 42, 43 connected to a respective die 13, 14 is free to move. The pin and slot arrangement does not interfere with the telescopic motion of each die but stabilizes each die so that the motion of each die is essentially linear along the axial direction of each piston. This linear motion of the die occurs after the cutting operation, as explained below, and enables the first die 12 to hold materials transferred from the second die 13.

The third die 14 also transfers materials to the first die 12. In order to do so the third die 14 must move to a position directly below the first die 12. The apparatus for indexing the second and third dies 13, 14 to positions aligned below the first die 12 is illustrated in FIG. 3.

With reference to FIG. 3 the swing arm 25 mounting pistons 33, 34 indicated by dashed lines, pivots about the pivot point 22. Swing arm 25 includes dogs 44, 45 corresponding to each of the pistons 33, 34 mounted on the swing arm. Each of the dogs 44, 45 has a flat face for abutting a stud 47 thereby limiting the rotary motion of swing arm 25. The stud 47 is positioned so that the second and third dies 13, 14 can be positioned directly below the first die 12. Setscrews 48, 49 in each of the dogs 44, 45 enable each die 13, 14 to be precisely and individually adjusted relative to the first die 12. The swing arm structure is desirable from the standpoint of promoting high speed and high accuracy indexing the second and third dies 13, 14 below the first die 12. Since laminar badge material is transferred from the second and third dies 13, 14 to the first die 12 and held in the first die 12, high accuracy in positioning the dies is necessary. Badge materials are accumulated in the first die 12 until a complete badge 51, as illustrated in FIG. 4, is assembled therein.

The manner of making badges with the badge press of the present invention is described with reference to FIGS. 5a-5f. In FIG. 5a the first die 12 is shown in position directly above the second die 13. As mentioned previously the second die 13 is a cylinder having a diameter slightly different from, i.e. larger than, the diameter of downwardly projecting edge 32. The second die 13 defines a shoulder 52 near the upper portion of the die, just below the upper lip 53 for supporting cut badge material. Before cutting, laminar badge material 54 rests on the upper lip 53 of the second die 13. A V-shaped groove 56 placed between the shoulder 52 and the lip 53 serves to provide a mold for bending or crimping cut badge material when the downwardly projecting edge 32 of the first die 12 comes into contact with the second die 13. The V-shaped groove 56 is the female geometric counterpart of the projecting edge 32. By saying that registry exists between the first die 12 and second or third dies 13, 14 is meant that the projecting edge 32 is in at least partial engagement with a groove which receives the projecting edge 32. When registry exists between the first die 12 and the second die 13 with material placed therebetween the material will be cut and the edges thereof slightly crimped as shown in FIG. 5b.

FIGS. 5a and 5b show the removable pin 38 in place locking the second die in place relative to the piston 33. This greatly facilitates the cutting operation of FIG. 5b. After cutting and crimping, the first die 12 is allowed to rise as the force exerted thereon, e.g. by a force means such as the lever 17 in FIG. 1, is removed and pin 38 is removed as shown in FIG. 5c. With reference to FIG. 5c a badge face plate 57 is shown to be placed over the badge materials 54. Since most face plates are made of metal with a transparent window as in FIG. 4 or made of tough plastic they are usually prefabricated and not cut in the press. Preferably the face plate 57 will have a slightly crimped peripheral edge for surrounding the edge of the badge material 54.

In FIG. 5d the first die 12 is being forced into registry with the second die 13. The second die 13 is free to yield against the downward force exerted by the first die 12 due to the telescopic mounting between the piston 33 and the second die 13. The second die 13 moves downwardly in the direction of the arrows coaxially over the piston 33. Hence, the piston 33 pushes upwardly against the badge materials 54 tending to force them into and against the projecting edge 32 of the first die 12. Downward motion of the second die 13 continues until the spring 36 on die 13 can no longer be compressed. At this point badge materials 54 will be solidly wedged into the downwardly projecting edge 32 of the die 12. As force is released from the first die 12, it will rise carrying with it the laminar badge materials 54 including the face plate 57. In this manner, the dies have performed as transfer dies wherein material residing in one die has been transferred to another die brought into registry with it.

FIG. 5e illustrates how the first die holds laminar badge materials 54 which have been transferred to it. The FIG. also illustrates the third die 14 brought into position beneath the

first die 12 for registry therewith. The third die 14 has a shoulder 58 and an upper lip 59 arranged to receive the downwardly projecting edge 32 of the first die 12 in registry. A badge component, such as a badge back 60, is centered on the shoulder 58 of die 14 so that it will be aligned with the remaining badge components in the first die. The angular orientation of the third die 14 is adjusted so that the badge back 60 will be appropriate for the remaining badge components 54 in the first die 12. Angular orientation is aided by fiducial marks, illustrated in FIG. 1, on top of the shoulder of die 14.

FIG. 5f shows the registry of the first die 12 with the third die 14 when force is transmitted to the first die. As the force continues the third die 14 is compressively telescoped against spring 37 allowing the piston 34 to enter the first die 12 thereby forcing the badge back 60 into a combined relationship with the laminar badge material 54. When force is released from the first die 12 the completely assembled badge may be removed from the apparatus. An air jet may be provided in the first die 12 to blast the badge out of the die 12 if the badge becomes lodged in position. Normally the weight and size of a completely assembled badge will cause it to drop out of the first die 12.

What we claim is:

1. Transfer dies comprising,

a frame,

first and second registering dies movably mounted on the frame for mutual registry, said second die including a shoulder for material support and said first die including wedge means for holding material received from the shoulder of the second die when said dies are in registry, and

material transfer means disposed below the shoulder of the second die for forcing material resting on the shoulder into the wedge means of the first die.

2. The apparatus of claim 1 wherein said material transfer means is a piston which is coaxially mounted in movable telescopic relationship relative to said second die but is fixed relative to the frame so that compressive movement of the second die relative to the piston causes material transfer from the shoulder of the second die into the first die when the first and second dies are in registry thereby permitting the first die to accumulate material for laminated badge formation.

3. In a press for rapidly forming laminar badges where the press is of the type having a sharpened first hollow die for cutting material and a second hollow die defining a shoulder grooved for registering with said sharpened first hollow die and supporting cut material thereon the improvement comprising,

material transfer means mounted for movement through said second hollow die for pushing laminar material supported on said shoulder of said second die into said first die, when said first and second dies are in registry, and force means for activating said material transfer means when said first and second die are in registry thereby pushing together laminar materials placed on said shoulder.

4. The apparatus of claim 3 wherein said material transfer means is a piston having a resilient suspension coaxial with said second die so that force applied by the force means against the second die moves the second die coaxially over the piston thereby enabling the piston to push material on the shoulder into the first die and return to its original position by resilient action.

5. A press for rapidly forming badges from laminar material comprising,

a frame having upper and lower second portions, a first die movably mounted on the upper portion of the frame for motion between the first and second frame ends,

second and third dies mounted on the lower portion of the frame for motion in a path transverse to the motion of the first die so that each of the second and third dies can come into registry with the first die,

material transfer means mounted for movement through the second and third dies for forcing material placed within second and third dies into said first die when said first die is in registry with each of said second and third and force is exerted to dies in registry,

force means mounted on the frame for applying force to the first die when in registry with another die thereby activating said material transfer means so that material is forced into the first die from each of said second and third dies, thereby forcibly combining badge materials.

6. The apparatus of claim 5 wherein said material transfer means is a piston.

7. The apparatus of claim 5 wherein the second and third dies are mounted for rotary motion.

8. The apparatus of claim 5 wherein adjustable die alignment means are provided on the second end of the frame for stopping the motion of each of the second and third dies in an aligned position for registry with said first die.

9. The apparatus of claim 5 wherein the first die includes a projecting cylindrical edge having a pointed wedge-shaped cross section with the wedge point facing a registering die so

that materials of diameter greater than said cylindrical edge placed in the press can be cut by said pointed wedge.

10. The apparatus of claim 9 wherein said piston means is adapted for mounting on the frame and wherein each of said 5 second and third dies comprises a hollow cylinder surrounding the upper position of the piston in a telescopic mounting therewith, the cylinder having a diameter slightly different than the cylindrical edge of the first die for achieving registry therewith, said cylinder defining a shoulder near the upper 10 portion thereof for supporting material so that compressive telescopic motion of the piston and cylinder causes the piston to push material supported on the shoulder away from said second and third dies toward and into said first die.

11. The apparatus of claim 10 where in the piston and 15 sleeve of said second die includes removable locking means for preventing telescopic action therebetween so that material of diameter greater than the cylindrical edge of the first die, which material is supported on the shoulder of the second die, will be cut by said wedge point when the first and second dies 20 are in registry.
